UNITED STATES PATENT OFFICE.

RAFFORD PITT, OF NEW ROCHELLE, AND MYRON COSSEY, OF BROOKLYN, NEW YORK.

DOOR-OPERATING MECHANISM.

SPECIFICATION forming part of Letters Patent No. 781,358, dated January 31, 1905.

Application filed November 4, 1904. Serial No. 231,454.

To all whom it may concern:

Be it known that we, RAFFORD PITT, residing at New Rochelle, in the county of Westchester, and MYRON COSSEY, residing in the borough of Brooklyn, in the county of Kings, State of New York, both citizens of the United States, have invented certain new and useful Improvements in Door-Operating Mechanism, of which the following is a full, clear, and exact specification.

The invention herein described relates to improvements in door-operating mechanism for suspended sliding doors or gates, such as those used on car-platforms, where the said mechanism engages the sliding door or gate in approximately the horizontal plane of its line of suspension. In the mechanism heretofore used for operating such sliding doors the door has been directly engaged by a horizontal lever the motion to which has been transmitted through a complicated series of angular levers, one extremity of which was pivoted on the horizontal lever and the other extremity connected to a rocking shaft supported on the car-body. The large number of parts contained in such series of levers, especially the large number of pivotal connections, unavoidably causes much friction and renders it more difficult to open and close the car-door.

One object of our invention is to provide a simpler arrangement of levers for transmitting the motion to the horizontal lever which engages directly with the door.

Another object of our invention is to provide improved operating mechanism for revolving the rocking shaft to which the series of angular levers referred to is connected.

In the drawings we have shown our invention in use with sliding mechanism supporting the inner end of the horizontal lever which engages the door. This sliding mechanism forms no part of our invention herein set forth, but is the same as that set forth and described in the separate application of the said Myron Cossey filed November 5, 1904, Serial No. 231,602. The uses and advantages of the said sliding mechanism and its method of operation are fully described in the said ap-

plication of Myron Cossey and need not here be repeated in detail.

In general terms our invention comprises operating mechanism for a suspended sliding door, which mechanism engages the same in approximately the plane of its line of suspension, said operating mechanism consisting of a horizontal lever attached to the roof or hood of the platform, so as to have limited longitudinal movement and free pivotal movement, in combination with a series of angular levers connected at one extremity to said horizontal lever and at the other extremity to a vertical rocking shaft which has segmental cog engagement with a horizontal rocking shaft and suitable operating mechanism connected with said horizontal rocking shaft.

Our invention is fully shown in the accompanying drawings, in which similar figures refer to similar parts.

Figure 1 in the drawings is a horizontal section of a portion of a car-body, taken on the plane of the line 1 1 of Fig. 2. Fig. 2 is an end view of a portion of a car, showing the operating mechanism. Fig. 3 is a vertical section of the same, taken on the plane of the line 3 3, Fig. 2. Fig. 4 is a detail horizontal section of the operating mechanism, taken on the plane of the line 4 4 of Fig. 5 looking in the direction of the arrow. Fig. 5 is a vertical section of the same, taken on the plane of the line 5 5 of Fig. 3 looking in the direction of the arrow.

A is the roof or hood of the car-platform.

B is the outer end of the platform.

C is the sliding door suspended overhead in any suitable or well-known manner.

D is a lever, preferably horizontal, one of whose ends engages pivotally with the sliding door at its outer edge and substantially in the horizontal plane, passing through its line of suspension. The other end of the lever D is guided and supported by plate E and rails G, L, and L' and plate K and bolts d d' and the other parts coöperating therewith, as fully described in said application of Myron Cossey, Serial No. 231,602. The lever D is pivoted to the plate E by the pivot F, which passes through the plate E and the rail G. The end

of the lever D which is thus pivoted to the plate E slides back and forth longitudinally a limited distance and moves freely in a pivotal motion about the pivot F, which itself slides back and forth with the rail G and plate E.

J is an angle-iron supported in the roof of the platform.

c is a brace for angle-iron J.

It will be seen that the distance between the 10 pivot F and the pivot m, by which the lever D is attached to the rest of the operating mechanism, is always the same. In other words, the length of the shorter arm of the lever D, being the distance from the fulcrum 15 F to the point m, where the power is applied, is uniform, both of them being movable instead of being fixed. Consequently there is no tendency for the lever to become set on a dead-center nor for the door to stick when 20 opening and closing.

o is a pitman-lever pivoted at one end to the horizontal lever D and at the other end to one end of a connecting-lever R. The other end of said connecting-lever R is rigidly attached 25 to a vertical rocking shaft Q, supported by a bracket a projecting from the car-body and its upper end turning freely in a socket b, formed upon the roof or hood of the car. The lower portion of the vertical rocking shaft Q 30 has projecting from it a segmental lever provided with cogs which engage with cogs on a similar segment attached to a horizontal rocking shaft supported on the end of the car-body and passing through the same.

35 On the outer end of the car-body is a bell-crank lever T, pivoted at v, with which is connected a pitman-lever V, pivoted at w to one arm of the bell-crank lever T, and at its other end pivoted at x to an operating-arm W, rigidly connected with the horizontal rocking shaft P.

X is a handle upon the end of the lever T.

The operation of the mechanism described is as follows: The operator standing on the 45 platform presses down the handle X of the hand-lever T. This throws out the short arm of the hand-lever and with it the pitman-lever V, which correspondingly pushes up the lever W, which in its turn revolves the rocking 50 shaft P. As the handle X descends the rocking shaft P transmits the motion to the vertical rocking shaft T, which turns on its axis carrying with it the lever R, which pushes on the lever O, thus carrying the motion to the 55 horizontal lever D and in turn pushing upon the door. As these motions continue the door slides from the closed position to the open position, the inner end of the lever D moving with the sliding mechanism on which it is 60 pivoted into its extreme open position, (indicated by dotted lines in Fig. 1.) When it is desired to close the door, the handle X is raised and the motion of all the parts is reversed. The door is locked in the closed po-

sition by pushing the handle X well over until it comes in contact with the pitman-lever V.

In practice the described apparatus would be duplicated at the opposite side of the platform and each car-platform would be similarly provided with a set of sliding doors and devices for operating them. The trainman standing in the usual way, with his feet on the two abutting platforms, can open both sliding doors from the same side at once. The doors slide back into the car, suitable space being provided for that purpose, as shown. The door is shown as suspended near the top, as is usually the case. Experience has shown that the best way to operate doors of this sort is by applying the operating force along a line 75 approximately parallel to and in substantially the horizontal plane of the line of suspension. It will be noted that the door-operating mechanism for each door engages the door in approximately the horizontal plane through the 80 line of suspension of the door and that the course of the arm which engages the door is or may be in a direct line with the slide of the door itself, whereby, in conjunction with the sliding mechanism herein referred to, all 85 jamming or pinching of the door in its travel is obviated. Moreover, the door-operating mechanism is so placed or located in respect to the car, the side passage-way, and all moving parts of the car mechanism that its operation does not in any way interfere with the 90 structural arrangement of the car or the operation of its moving parts or the convenience 95 of the passengers.

We do not broadly claim operating mechanism for a suspended sliding door which engages the door in the plane of the line of suspension, which operating mechanism consists of a series of levers connected with a horizontal lever, one end of which engages the door 100 and the other is so attached to the door or roof of the platform as to have limited longitudinal and free pivotal motion, as we are aware that mechanism accomplishing this result is already in use; but

110 What we do claim, and desire to secure by Letters Patent, is—

1. In the platform of a street or railway car having a suspended sliding door, operating mechanism for said door, engaging the 115 same in approximately the horizontal plane of its line of suspension, said operating mechanism consisting of a horizontal lever attached to the roof or hood of the platform so as to have limited longitudinal movement and free pivotal movement; in combination with a series of angular levers connected at one extremity to said horizontal lever and at the other extremity to a vertical rocking shaft which has segmental cog engagement with a 120 horizontal rocking shaft and suitable mechanism connected with said horizontal rocking shaft, substantially as described.

2. In the platform of a street or railway car having a suspended sliding door, operating mechanism for said door, engaging the same in approximately the horizontal plane of its line of suspension, which operating mechanism consists of a horizontal lever so supported on the roof or hood of the platform as to have limited longitudinal and free pivotal movement; in combination with a pitman-lever pivoted at one end to said horizontal lever and at the other end to a connecting-lever which is rigidly attached to and turns with a vertical rocking shaft supported on the car-body; segmental cog connections between said vertical rocking shaft and a horizontal rocking shaft; and a compound operating-lever located at the outer end of the car-platform and connected with said rocking shaft, substantially as described.
3. In the platform of a street or railway car having a suspended sliding door, operating mechanism for said door, engaging the same in approximately the horizontal plane of its line of suspension, said operating mechanism consisting of a horizontal lever so sup-

ported on the roof or hood of the car-platform as to have limited longitudinal and free pivotal movement, a pitman-lever pivoted at one of its ends to the said horizontal lever and at its other end to a connecting-lever which is rigidly attached to a vertical rocking shaft suitably supported on the car-body, the said rocking shaft having cog connections by segmental levers with a horizontal rocking shaft rigidly supported on said car-body; and a compound operating-lever on the outer end of the car-platform, consisting of a bell-crank hand-lever, a pitman-lever having pivotal connection with the short arm of said hand-lever, and the operating-lever pivoted at one end on the pitman-lever and at the other end rigidly connected with the horizontal rocking shaft, substantially as and for the purposes set forth.
